AUTOMATIC CONTROL FOR DEICING
MECHANISM

Lawrence F. Tumey, Baldwin, N. Y., assignor to
Eclipse Aviation Corporation, East Orange,
N. J., a corporation of New Jersey

Application August 10, 1937, Serial No. 158,406

15 Claims. (Cl. 244—134)

This invention relates to aircraft, and more particularly to a means and method for preventing the accumulation of ice on aircraft surfaces, such as the wing and tail structures, the propeller blades, and other exposed surfaces.

It is well known that under certain conditions of temperature and relative humidity, ice will form on the structural parts of an airplane. This formation is cumulative and at times seriously interferes with the control and operation of aircraft. The more common locations for the ice formation are the leading edges of the wings and tail structure.

In Patent No. 1,998,809 granted to W. C. Geer on April 23, 1935, there is illustrated a type of flexible and expandable overshoe provided upon such leading edges of the wings and tail structures and adapted to expand and contract periodically in response to the operation of pneumatic energizing means.

An object of the present invention is to provide for the automatic initiation of the operation of such overshoe actuating means, so as to relieve the operator of the craft of the necessity of maintaining vigilance to determine the proper moment for bringing such mechanism into operation.

Other objects of the invention will become apparent upon examination of the following description which is to be read in connection with the accompanying drawing illustrating the preferred embodiment of the invention.

In said drawing:

Fig. 1 is a diagrammatic representation of the parts entering into the preferred embodiment of the invention and the electrical operating connections therefor;

Fig. 2 is a view in elevation of the moisture and temperature responsive units of the switches controlled thereby;

Fig. 3 is a sectional view through a portion of a wing or tail structure containing the units shown in Fig. 2; and

Fig. 4 is a view in perspective of the structure shown in Fig. 3, the structure being shown as cut transversely along the line 4—4 of Fig. 3.

Referring to the drawing, reference character 5 designates an electric device for initiating the operation of the overshoe actuating means, or any equivalent ice dislodging mechanism, and reference character 6 indicates a source of current for supplying the unit 5 with the operating energy required.

Reference character 7 designates a switch which may be manually operated to produce a

direct energization of the unit 5—as when it is moved into engagement with the contact 8—or to place the system in condition for automatic operation, as when it is moved into engagement with the contact 9. Reference characters 11 and 12 designate ether filled expansible diaphragms or bellows, the former being adapted to expand upon increase in the amount of unevaporated moisture drawn thereto by capillary action of the fabric 13, the lower portion of said fabric being immersed in a liquid containing receptacle 14 suitably secured as indicated at 15 to the framework 16 of the wing or tail structure. This framework 16 also supports the second expansible member 12 which is adapted to expand upon absorption of heat and to contract when cool, the two units 11 and 12 being disposed within the air stream confined by the conduit means indicated at 17 in Figs. 3 and 4, the said conduit having one end thereof projecting through the wing structure adjacent the leading edge thereof as indicated at 18 and a discharge end near the trailing edge as indicated at 19. A partition 21 is provided longitudinally of the conduit 17 to separate the air stream into two sections, one to act upon the unit 11 and the other to act upon the unit 12 as indicated. Switch elements are attached to units 11 and 12 as indicated at 25 and 27 respectively, and are adapted to control energization of an electromagnet 31 which in turn operates upon the set of contacts 32, 33 to produce energization of the unit 5.

Springs or their equivalents are provided for the purpose of allowing over-travel (in a downward direction) of each set of contacts, such a spring for the contacts 42 and 43 being indicated at 44, and such a spring for the contacts 46 and 47 being indicated at 48. A spring tending to hold the contacts 32 and 33 apart is indicated at 41. Cooperating with the springs 44 and 48 are adjusting means 51 and 52 respectively whereby the extent of movement necessary to produce closure of a circuit through the conducting member 27 is controlled.

The operation of the system is based upon the known fact that the formation of ice or snow is governed by two factors, namely, temperature and humidity. Both the temperature responsive device 12 and the humidity responsive device 11 are however, sensitive to temperature changes but in addition the device 11 is also sensitive to humidity changes due to the fact that the fabric 13 is maintained in a moist condition by the capillary action of drawing liquid from the reservoir 14; hence its temperature is relatively lower

- than that of the similarly constructed bellows 12, due to the cooling effect of evaporation from the fabric 13 when the humidity is low. When the amount of moisture in the air increases the rate 5 of evaporation is lower and hence the cooling effect upon the member 11 is less. This allows the member 11 to retain sufficient heat to cause expansion and produce engagement of the contacts 46 and 47. Then if the temperature is at 10 the freezing point resulting contraction of the bellows 12 (due to its more rapid radiation of heat) will have produced a movement of the conducting member 27 downward sufficiently to close the contact 42 upon the contact 43. This con- 15 current closure of the contacts 46, 47 and 42, 43 establishes a path for current flow to the relay 31 as indicated clearly in Fig. 1—assuming of course, that switch 7 is in engagement with the contact 9. The resulting energization of the relay 31 20 establishes a circuit to energize the deicing mechanism 5, the circuit passing by way of conductors 55 and 56 and the now closed contacts 32 and 33. The resulting rotation of motor 5 will produce corresponding rotation of the distributor 25 valve 26, and also produces operation of the compressor 23, the latter serving to replenish the supply of compressed air in the reservoir 24, and the former serving to periodically connect said reservoir 24 with each "overshoe" or expansible mem- 30 ber on the aerofoil surfaces, as described in the Geer patent above identified. Operation of the deicing mechanism will then continue until there is a change of either humidity or temperature conditions sufficient to open one or the other 35 of the sets of contacts 46, 47 or 42, 43, whereupon the winding 31 will be de-energized and the spring 41 will then become effective to re-open contacts 32, 33 and thus restore the parts to the initial non-operating condition.
- 40 In addition to its use on aircraft, the invention is also applicable to any air conditioning problem involving exposed surfaces upon which ice might otherwise accumulate.
- What I claim is:
- 45 1. In an aircraft, deicing mechanism operative at all altitudes for preventing ice accumulation on the exterior surface of said aircraft and for removing such ice as may have formed on said surface, means responsive to ice forming conditions on said aircraft for automatically rendering said deicing mechanism operative, and means for rendering said last named means ineffective at all temperatures above freezing.
- 50 2. In an aircraft, deicing mechanism operative at all altitudes for preventing ice accumulation on an exterior convex surface of said aircraft and for removing such ice as may have formed on said surface, and temperature responsive means for automatically rendering said deicing mecha- 55 nism operative.
- 55 3. In an aircraft, deicing mechanism operative at all altitudes for preventing ice accumulation on the exterior surface of said aircraft and for removing such ice as may have formed on said surface, moisture responsive means for automatically rendering said deicing mechanism operative, and means for rendering said moisture responsive means ineffective at all temperatures above freezing.
- 60 4. The combination, with exposed surfaces of an aircraft, of means for preventing ice accumulation on said surfaces, and means responsive to ice forming conditions for automatically render- 65 ing said first-named means operative under

conditions of level flight, as well as in any other attitude of the craft.

5. The combination, with exposed surfaces of an aircraft, of means including motor operated fluid distributor means for preventing ice accumulation on said surfaces, said means further including a source of current and an electric circuit connecting said source with said motor operated means, circuit controlling switch members in said circuit, means normally holding said switch members in open circuit position, moisture responsive means for moving one of said switch members toward the other, temperature responsive means for producing concurrent movement of said second switch member either toward or away from the first switch member, the direction of movement being in accordance with the direction of temperature change, and means including a third switch member for causing said circuit to remain open at all temperatures above freezing, regardless of the amount of movement of said moisture and temperature responsive switch member.

6. The combination, with lifting surfaces of an aircraft, of means for preventing ice accumulation on said surfaces, said means including a source of current and an electric circuit, circuit controlling switch members in said circuit, moisture responsive means for moving one of said switch members toward the other, temperature responsive means for producing concurrent movement of said second switch member either toward or away from the first switch member, the direction of movement being in accordance with the direction of temperature change, and means including a third switch member for causing said circuit to remain open at all temperatures above freezing, regardless of the amount of movement of said moisture and temperature responsive switch members.

7. The combination, with lifting surfaces of an aircraft, of means for preventing ice accumulation on said surfaces, said means including a source of current and an electric circuit, circuit controlling switch means in said circuit, includ- 45 ing a temperature responsive conducting element, moisture responsive means engageable with one end of said temperature responsive conducting element for shifting the latter independently of any temperature change, and additional con- 50 ducting means engageable with the opposite end of said temperature responsive conducting element only when the temperature is at or below freezing.

8. The combination, with a source of current 55 and an electric circuit, of circuit controlling switch members in said circuit, moisture responsive means for moving one of said switch members toward the other, temperature responsive means for producing concurrent movement of 60 said second switch member either toward or away from the first switch member, the direction of movement being in accordance with the direction of temperature change, and means including a third switch member for causing said circuit to remain open at all temperatures above freezing, regardless of the amount of movement of said moisture and temperature responsive switch members.

9. The combination with a source of current 70 and an electric circuit, of circuit controlling switch means in said circuit, including a tem- 75 perature responsive conducting element, moisture responsive means engageable with one end of said temperature responsive conducting element for

shifting the latter independently of any temperature change, and additional conducting means engageable with the opposite end of said temperature responsive conducting element only when the temperature is at or below freezing.

5 10. The combination with an ice removing means for aircraft, of a circuit controlling energization thereof, said circuit including a pair of current conducting elements, and means for holding said pair of current conducting elements in engagement, one with the other, at all freezing temperatures.

11. The combination with an ice removing means for aircraft, of a circuit controlling energization thereof, said circuit including a pair of current conducting elements, means for holding said pair of current conducting elements in engagement, one with the other, at all freezing temperatures regardless of the presence or absence 20 of moisture on the craft, and means including a third current conducting element engageable with one of said first named current conducting elements to complete the energization controlling circuit.

25 12. The combination with an ice removing means for aircraft, of a circuit controlling energization thereof, said circuit including a pair of current conducting elements, means for holding said pair of current conducting elements in engagement, one with the other, at all freezing temperatures regardless of the presence or absence 30 of moisture on the craft, means including a third

current conducting element engageable with one of said first named current conducting elements to complete the energization controlling circuit, and moisture-responsive means for actuating said third current conducting element.

5 13. The combination with an ice removing means for aircraft, of means for controlling energization of said ice removing means, said last-named means including a shiftable control element, and temperature responsive means for holding said control element in a position tending to produce energization of said ice removing means at all freezing temperatures.

10 14. The combination with an ice removing means for aircraft, of means for controlling energization of said ice removing means, said last-named means including a shiftable control element, and temperature responsive means for holding said control element in a position tending to produce energization of said ice removing means at all freezing temperatures and in advance of the actual formation of any considerable amount of ice.

15 15. The combination with an ice removing means for aircraft, of means for controlling energization of said ice removing means, said last-named means including a shiftable control element, and means for holding said control element in a position tending to produce energization of said ice removing means in advance of the actual 20 formation of any considerable amount of ice.
